US00D587665S

(12) **United States Design Patent**
Isshiki

(10) **Patent No.:** **US D587,665 S**
(45) **Date of Patent:** **** Mar. 3, 2009**

(54) **TELEVISION RECEIVER**

(75) Inventor: **Masao Isshiki**, Kanagawa-ken (JP)
(73) Assignee: **Kabushiki Kaisha Toshiba**, Tokyo (JP)
(**) Term: **14 Years**
(21) Appl. No.: **29/321,407**
(22) Filed: **Jul. 16, 2008**

(30) **Foreign Application Priority Data**

May 16, 2008 (JP) 2008-012206

(51) **LOC (9) Cl.** **14-03**
